CAVITY RESONATOR

Herbert Buchholz, Berlin, Germany, assignor to
 General Electric Company, a corporation of
 New York

Application July 12, 1940, Serial No. 345,038
 In Germany September 5, 1939

1 Claim. (Cl. 178—44)

It is known in the art that oscillatory structures or systems employing coils and condensers are not practicable in ultra short wave work. Hence, for the various purposes in which such oscillatory structures are required it has been customary to use either Lecher wire systems or coaxial lines of certain length, so-called $\lambda/4$ conductors. While it is true that it is readily feasible to secure the desired resonance effects, the losses incurred in such schemes prove still unduly high in certain practical cases.

Starting from purely theoretical considerations, it has been discovered that resonance effects are obtained in a completely closed non-magnetic metal body or enclosure in which an exciting system is mounted in a way quite similar to that known from Lecher wire systems. The present invention is predicated upon this consideration. It consists in using hollow or cavity or chamber bodies for oscillatory structures (resonators) in ultra short wave work.

The novel resonators created for the said purpose distinguish themselves from oscillatory structures of the kind known in the prior art, especially because of the fact that their construction is extremely simple, for they involve and require bodies of the simplest geometrical form. However, one essential advantage is that they involve considerably smaller losses than the oscillatory structures heretofore used.

Chamber resonators of the kind here disclosed (sometimes called cavity resonators), in line with what follows from general considerations, have the property of possessing an infinite series of exactly fixed and defined resonance frequencies, starting from a certain minimum frequency which is governed by the dimensions of the metallic body or chamber. The nature and the mounting of the exciting system in the interior of the chamber or hollow body or cavity has no influence upon the critical frequencies. To excite the resonance wave, which may be an electrical or magnetic transversal wave or else a corresponding longitudinal wave, recourse is had to suitable exciter systems of the kind known from the ultra short wave art. For example, for exciting electric transversal waves a simple circular current loop is employed. To excite a magnetic wave in the form of a resonance wave, there may be used an electrical dipole suitably disposed in the interior of the resonator or an exciter system of an equivalent nature. An exciter system of the kind here concerned could be formed, for instance, of a rim or circle of wire loop units connected in parallel so disposed that they result in a sort of annular or toroidal coil.

In what follows a number of exemplified embodiments of such chamber resonators shall be described by reference to the drawing. However, it is expressly emphasized that the invention is

5 by no means restricted to the forms of construction here shown by way of example. In fact, it will be readily understood that there is a multiplicity of similar simple chambers with which very definite resonance effects are obtainable.

Fig. 1 is a top plan view and Fig. 1a a side view of a cylindrical cavity resonator of the invention; Fig. 2 is a perspective view and Fig. 2a a side view of another cavity resonator in accordance with the invention; Fig. 3 is a perspective view of a prism cavity resonator of the invention; Fig. 4 is an equivalent electrical circuit diagram of the three resonators of Figs. 1, 2 and 3; Fig. 5 shows how a cavity resonator of the invention can be excited and the output taken therefrom; and Fig. 5a shows the equivalent electrical circuit of a system as shown in Fig. 5.

To cite one example, the assumption shall be made that the metallic body has the shape of a cylinder R (Fig. 1) having a radius a and a length 2 (note Fig. 1a). Inside the cylinder is an exciting system E in the form of a simple circular loop, the current supply leads St of which are indicated. By means of such an exciter system electrical waves are generated. The dielectric of this form of construction (as well as in those hereinafter to be discussed) is air (with $\epsilon=1$). As already pointed out above, such a chamber resonator has an infinite number of critical frequencies in the presence of which a state of resonance arises. In the instance here under consideration these resonance frequencies are expressible by the formula:

$$35 \quad \text{critical} = \frac{2\pi a}{\sqrt{\left(\frac{\pi n a}{2l}\right)^2 + j_{1,p}^2}}$$

where n equals integral parameters (1, 2, 3, 4 . . .) and $j_{1,p}$ the roots of the equation $J_1(x)=0$ (cylindrical function of the first kind or Bessel function). In case of magnetic excitation, $j_{0,p}$ must be put in lieu of the square root term $j_{1,p}$, the former representing the roots of equation $J_0(x)=0$.

45 This equation will result in the lowest resonance frequency by choosing the lowest parameter ($n=1$) and using for $j_{1,p}$ also the lowest value. The lowest value of $j_{1,p}$ which may be found in tabulations are:

$$50 \quad \begin{aligned} j_{1,p} &= 3.83 \\ &7.02 \\ &10.17 \\ &13.32 \\ &\text{etc.} \end{aligned}$$

55 The supply of current may be simplified in practice by providing the cylindrical metal body or chamber with a concentric hole; that is to say, by using a hollow cylinder for the resonator (Figs. 2 and 2a). In this form of construction

the critical frequencies of the resonator turn out to be somewhat higher throughout, although the differences as compared with the simple cylindrical form are only slight. In the presence of a radius ratio of $r_a:r_i=10$, the lowermost limiting frequency is at the most from five to ten percent higher than in the first embodiment.

In a further embodiment the resonator is of prismatic form, the edges of which have dimensions $2a$, $2b$ and $2c$ (Fig. 3). The excitation shall be assumed to be the same as in the first exemplified embodiment by the aid of a loop. The critical frequencies are here calculable on the basis of equation:

$$\lambda_{\text{critical}} = \frac{2}{\sqrt{\left(\frac{m}{2a}\right)^2 + \left(\frac{n}{2b}\right)^2 + \left(\frac{p}{2c}\right)^2}}$$

where m , n , p , again integral parameters, have these values:

$$m(n,p)=0, 1, 2, 3 \dots$$

The lowermost critical frequency is obtained by making:

$$m=0, n=1, p=1 \text{ order}$$

$$m=1, n=0, p=1 \text{ order}$$

$$m=1, n=1, p=0$$

according to what values a , b , c possess. An equivalent diagram for the three embodiments here cited predicated upon electrical excitation is shown in Fig. 4. It represents a simple parallel resonance circuit.

It is quite readily feasible to suitably dispose inside the metallic chamber or body also a plurality of electrical or magnetic exciter systems, so that the chamber resonator could, for instance, be used as a selective transformer or coil.

5 An embodiment of this kind is illustrated in Fig. 5. Two electric exciting systems in the form of two current loops could be mounted inside the resonator chamber in such a way that the resonator acts like a transformer in line with the equivalent circuit diagram in Fig. 5a.

10 The above formulae go to show that the main field of application of the resonators lies within the decimeter wave band, for the reason that the geometric dimensions of the resonators would become unduly large if they were to be used for longer waves. However, theoretically speaking, no limitation is imposed, that is, the invention is not restricted to the said field.

15 20 What is claimed is:

An ultra short wave oscillatory circuit comprising a hollow cylindrical body having metallic end plates, a tubular conductor located along the axis of said cylindrical body and extending 25 through said end plates, and a circular loop in the interior of said body and around said tubular conductor, the terminals of said loop being adjacent each other and entering the interior of said tubular conductor for coupling to external trans- 30 lation apparatus.
